DESIGN FOR A CASING FOR AN AIR CONDITIONING UNIT OR SIMILAR ARTICLE

Donald C. Hollister, Grosse Pointe, Mich., assignor
to W. A. Maher, Detroit, Mich., doing business
as Precision Products Company

Application February 12, 1937, Serial No. 67,605

Term of patent 7 years

To all whom it may concern:

Be it known that I, Donald C. Hollister, a citizen of the United States and resident of Grosse Pointe, county of Wayne, State of Michigan, have invented a new, original, and ornamental Design for a Casing for an Air Conditioning Unit or Similar Article, of which the following is a specification, reference being had to the accompanying drawing, forming a part thereof.

In the drawing:

Figure 1 is a front elevation of the casing for an air conditioning unit, showing my new design; Figure 2 is a side elevation of the casing; and Figure 3 is a top plan view of the casing.

I claim:

The ornamental design for a casing for an air conditioning unit or similar article, as shown.

DONALD C. HOLLISTER.
